(57) **CLAIM**

I claim the ornamental design for an electrical box, as shown and described herein.

DESCRIPTION

FIG. 1 is a perspective view of the claimed electrical box. FIG. 2 is a perspective view of the claimed electrical box. FIG. 3 is a frontal view of the claimed electrical box relative to FIG. 1.

FIG. 4 is a rear view of the claimed electrical box relative to FIG. 1.

FIG. 5 is an end view of the claimed electrical box that is illustrated in FIG. 1.

FIG. 6 is an end view of the claimed electrical box that is hidden in FIG. 1.

FIG. 7 is a plan view of the claimed electrical box; and, FIG. 8 is a bottom view of the claimed electrical box.

1 Claim, 8 Drawing Sheets**FIG. 1**
